WILLIAM B. FOSTER, OF UTICA, NEW YORK, ASSIGNOR TO FOSTER BROTHERS MANUFACTURING COMPANY, OF UTICA, NEW YORK, A CORPORATION OF NEW YORK

SPRING CUSHION CONSTRUCTION

Application filed May 6, 1930. Serial No. 450,294.

This invention relates to spring cushion constructions and particularly to the part of such construction which relates to the connecting of adjacent coiled springs by clips and the spacing apart of certain of the rows of springs.

The purpose of this invention is to provide a new and better means for connecting the end coils of such springs and to combine with the clip used therefor spacing rods which pass through said clips and have offset portions enclosed within said clips so as to hold certain of the rows of springs apart.

A further purpose is to provide in a construction of the character described means for making a non-movable joint between the clip and one of the springs so that the springs will not pile or rotate upon each other.

Further advantages and objects of the invention will appear from the specification and claims herein.

Fig. 1 is a top plan view of a portion of a spring cushion embodying this invention, the top of one clip being removed.

Fig. 2 is a plan view of the clip while still out flat.

Fig. 3 is a plan view of the top coils of two adjacent springs with the clip and connecting rod in place but before the projecting parts of the clip are closed.

Fig. 4 is a plan view similar to Fig. 3 after the end flaps of the clip have been turned towards each other to enclose portions of the end coils of the two springs and the offset portion of the connecting rod.

Fig. 5 is a view of said joint after the side wings have been turned over the inturned end flaps.

Figs. 6 and 7 are views similar to Figs. 3 and 4 of a modified form of the construction. Figs. 8 and 9 are views similar to Figs. 3 and 4 of another modified form of construction and Figs. 10 and 11 are similar views of the fourth form of the construction. Fig. 12 is a view similar to Fig. 10 of a still further modification.

In the spring structure illustrated it will be seen that the desired number of coiled springs 10 are arranged in longitudinally extending rows A and transversely extend-

ing rows B. For definiteness of description it will be assumed that as shown in the drawings the end coils 11 of adjacent springs in the transverse rows B are to be connected by clips 12 and that the springs in the longitudinal rows A will be spaced apart by spacing rods 13. It will be understood of course that in any particular structure the spacing rods might extend transverse thereof with the clips between the springs of the longitudinal rows. It will be obvious that such change simply involves the relative number of springs in the different series of rows.

It will be seen that the springs illustrated in the drawings are of the type where the extremity of the end coil 11 is not tied or knotted to the within or adjoining coil of the spring but that the free end or extremity is formed as an offset 18 preferably and conveniently formed as shown in the drawings 70 extending radially outwardly from the end coil but still in the general plane of the end coil so as to be enclosed within the clip 12.

The clip 12 is conveniently formed of sheet 75 metal stamped out so as to have a rectangular body portion 15 and two oppositely arranged projecting end flaps 16 and two oppositely disposed side wings 17. A clip of this form is laid over the adjacent parts of the 80 end coils of two springs in the transverse row including the offset portion or projecting portion of one of these two springs approximately as shown in Fig. 3. It will be understood that Figs. 3 and 4 are plan views 85 of the joints shown in Fig. 1 as seen from below since it is advisable that the flat part of the clip, namely the rectangular body portion 15 be at the top of the cushion spring as shown in Fig. 1 or at the bottom surface 90 of the bottom joints of such a structure. It will be seen that across the body 15 of the clip extends the offset portion 14 of the spacing rod 13. This offset 14 may be conveniently formed as a V-shaped loop formed in 95 the wire or rod 13 although other forms of offset may be used such as a curved U-shaped form as shown in Figs. 6, 8 and 12. It will be seen that when the parts are placed in position ready for assembling the offset 18 from 100

the right hand spring is at one side of the rectangular body portion 15 of the clip and projects part way towards the other spring. In addition to the extremity of the end coil having the offset 18 there is brought into the clip the oppositely located portion 19 of the said end coil 11 of said right hand spring. Through the clip also extends the plain or slightly curved portion 20 of the end coil of the left hand spring. With the parts in the position as shown in Fig. 3 the two end flaps are bent about the said portions 19 and 20 and towards each other and against the offset portion 14 of the spacing rod 13 so that the parts then appear as shown in Fig. 4. Then the side wings 17 are bent over the inturned end flaps 16 towards each other so as to firmly hold the end flap 16 down in position and so as to close the two sides of the flap and hold the offset 18 of the extremity of the right hand spring from slipping out of the clip and also so as to hold the offset 14 of the spacing rod 13 from moving out from the clip. The clip and the adjacent parts of the spring as thus assembled will then appear from either outside surface of the spring cushion as shown in Fig. 1, that is with a smooth surface towards the used side of the spring cushion. The overlapping end flaps and the overlapping side wings of the clip are towards the center of the cushion. It will be understood of course that the offsets 14 in the spacing rods 13 are located at the proper distance apart according to the distance that the transverse rows B are to be spaced from each other.

It will be seen that when the springs are of the form shown in Fig. 1 the clip here illustrated serves to fasten the extremity of the end coil to the opposite adjacent portion of the end coil and avoids a separate knotting operation and also avoids the roughness or upward projections incident to a knot.

The offset portion 18 upon the right hand spring on account of extending radially from said end coil will prevent the right hand spring from rotating to any great extent relative to the clip 12. On the other hand the plain portion 20 of the left hand spring can rotate relative to the said clip so as to get the desired flexibility at these joints making the connection between the right hand springs and the clip a substantially non-movable joint and prevents the springs from piling or turning over each other at the clipped joint.

In the modification shown in Figs. 6 and 7 the offset 24 upon the extremity of the outer coil 11 extends inward toward the center of the circle and the next within coil of the spring is spaced slightly from the end of this offset but both the offset 24 upon the right hand spring and the looped offset 25 upon the connecting rod 13 are enclosed within the end flaps 16 and side wings 17 of the clip 12. It will be understood that

after the parts have been brought to the position shown in Figs. 7 the side wings 17 will be closed over the end flaps as appears in Fig. 5.

The modification shown in Figs. 8 and 9 involves having a hole 21 in the clip 12 near the line where one side flap is to be bent relative to the body 15 of the clip and through this hole extends the end of the outer coil 11 with the offset 26 extending inwardly so as to be within the clip when the clip has its parts folded down over this offset and also over the offset 27 of the connecting rod.

In the modification shown in Figs. 10 and 11 the offset 22 upon the outer coil 11 to be enclosed within the clip is in the form of an inwardly extending loop and the clip is formed proportionately longer as appears in Fig. 11 where the clip is shown in partly closed position, that is prior to the final overlapping of the side wings 17.

Fig. 12 shows a modification of the construction shown in Fig. 10 in that the offset 23 is formed upon the body of the end coil 11 instead of at its extremity but this offset extends outward from the circle of the end coil of the spring. The spacing bar has a loop-shaped offset 28.

In all of these modifications it will be seen that the offset upon the connecting rod is securely enclosed within the clip and so holds the clips spaced apart the desired distance and thereby the springs that are in turn connected by means of the successive clips.

In all forms of the invention also it will be seen that an offset upon the end coil of one spring is provided in the plane of the end coil and enclosed within the clip so that a non-rotatable joint is effected between the clip and the end coil having such offset and that this results in the two connected springs being so jointed that they cannot "pile" or pass one on top of the other. Also the offset upon the end coil of a spring when enclosed within my form of clip prevents the end coil of that spring from sliding either way through the clip.

What I claim as new and desire to secure by Letters Patent is:

1. In a spring cushion construction the combination of a plurality of coiled springs arranged in longitudinal and transverse rows, a spacing rod arranged between each adjacent pair of longitudinal rows and having an offset portion located between each pair of springs in the transverse rows, an end coil of one of each pair of said adjacent springs in the transverse rows having an offset in the plane of its coil and opposite the approaching part of the other spring and a clip connecting each adjacent pair of springs in the transverse rows, said clip having a body portion and two oppositely located end flaps and two side wings with the end flaps

turned back towards each other over and enclosing portions of the end coils of the two springs and the interposed offset portion of the spacing rod and the interposed offset portion of said end coil and with the side wings turned towards each other against the end flaps and retaining the offset portion of the spacing rod and the offset portion of said end coil of one spring within the clip.

2. In a spring cushion construction the combination of a plurality of coiled springs arranged in longitudinal and transverse rows, a spacing rod arranged between each adjacent pair of longitudinal rows and having an offset portion located between each pair of springs in the transverse rows and extending in the plane of the end coils thereof, and end coil of one of each pair of said adjacent springs in the transverse rows having an offset in the plane of its coil and opposite the approaching part of the other spring and a clip connecting each adjacent pair of springs in the transverse rows, said clip having a body portion and two oppositely located end flaps and two side wings, with the end flaps turned back towards each other over and enclosing portions of the end coils of the two springs including the said offset portion of one of said springs and the interposed offset portion of the spacing rod and with the side wings turned towards each other against the end flaps and retaining the offset portion of the spacing rod and the offset portion of the end coil within the clip.

35 In witness whereof I have affixed my signature, this 31st day of March 1930.

WILLIAM B. FOSTER.
